TICKET-PRINTING MACHINE.

1,367,186.

Specification of Letters Patent.

Patented Feb. 1, 1921.

Application filed July 31, 1919. Serial No. 314,523.

To all whom it may concern:

Be it known that I, MAURICE R. HOWARD, a subject of the King of Great Britain, residing at Chesham, Buckinghamshire, England, have invented certain new and useful Improvements in Ticket-Printing Machines, of which the following is a specification, reference being had therein to the accompanying drawing.

10 This invention is a ticket printing machine, and more particularly a machine which may be selectively operated for the purpose of printing and issuing tickets for various purposes. The particular design of 15 machine herein shown is for printing the destination and other data, such as serial number and date, upon railway passage tickets, to be used at the ticket seller's window; but the principles may be used in machines designed for various other purposes, such as printing and issuing tickets for theaters, amusement parks and halls, sales counters and the like.

20 The main objects of the present invention are to afford a ticket printing machine which will be convenient in use, minimizing trouble and thought of the operator, yet sure and quick in its action. Another object is to enable a machine of the class mentioned to be built at comparatively low cost, yet durable and efficient in use. Other and further objects will be elucidated in the hereinafter following description or will be apparent to those skilled in the art.

25 To the attainment of such objects and advantages the present invention consists in the novel ticket printing machine and the novel features of structure, combination, arrangement, mechanism and detail herein 30 illustrated, described or claimed.

In the accompanying drawings forming a part hereof, Figure 1 is a front elevation of a ticket printing machine of the class and type mentioned, embodying and illustrating 35 the principles of the present invention.

Fig. 2 is a rear elevation thereof.

Fig. 3 is a right elevation thereof.

Fig. 4 is a section taken on the plane 4—4 of Fig. 1.

50 Fig. 5 is a similar section showing the parts in a different position.

Fig. 6 is a section on the line 6—6 of Fig. 1.

55 Figs. 7 and 8 are detached perspective views of certain parts of the mechanism.

In the particular form or embodiment shown the present invention includes one or more of the following elements. A rotary type carrier or drum has around or near its periphery a series of printing members comprising the type for printing the name of the destination stations, or of both stations between which the ride is taken, and all other printed matter desired, so that plain unprinted cards may be used. Above 60 this is a ticket or blank supply or magazine from which a card or blank is extracted and dropped upon the proper portion or printing member of the rotary carrier as the latter advances. An inking device is used for 65 applying ink to the type. A roller or other presser is used for applying pressure to force each ticket against the inked type. A passage or chute conducts the printed ticket and discharges it within reach of the seller 70 or buyer. The rotary carrier or drum has push buttons or other selective devices, and these act to set certain mechanism into action which determines the place of depositing each blank ticket, that is, upon which 75 printing member. The carrier drum also carries consecutive numbering devices, so that the successive tickets to each destination are numbered in proper order. Also a 80 meter or counter is employed to keep count 85 or register of the sales. Means also are shown for printing the date of sale on the reverse side of each ticket.

Specifically the illustrated embodiment of the present invention may comprise a base 90 10. A suitable housing or casing may be employed to conceal and protect the mechanism against injury and tampering. At the front side of the base is an upright standard 11, and at the rear a standard 12. 95 Journaled to these two standards is the main shaft or axle 13.

The rotary type carrier, cylinder or drum 15 is mounted on the axle 13. This carrier, as shown, carries around its periphery a 100 series of printing plates 16, having the characters or type for printing the names of the various destinations to which tickets are to be sold. For illustration a carrier is shown having fifteen of the type plates. The number could be largely increased, or the ticket office could be supplied with a number of the apparatuses.

The type drum 15 may be rotated by hand, for example, through a handle on the axle 110

13, but is preferably power driven to the extent of one revolution at each operation, and for this purpose a large gear 17 is shown mounted on the drum or axle, the same being engaged and driven by a pinion 18, mounted on the shaft of a suitable driving motor 19. As will be explained, the power is automatically thrown on and off at each operation. In order to bring the drum to rest at the end 10 of a rotation, at its normal position, a stop device 20 may be employed. Ink may be supplied to the various type plates in any suitable manner, for example, as indicated by the inking device 22.

15 At the front or face of the rotary drum 15 are a series of selective push buttons 25, each of which when pressed rearwardly sets or moves rearwardly near the rear periphery of the drum a corresponding finger or contact 26. The button 25* is supposed to have been pressed, and the finger 26* is seen in Fig. 3 as standing rearwardly farther than the other fingers. Adjacent each button on the drum face is an inscription 27, stating 20 the station or matter to be printed. These preferably all read one way, so that by returning the drum to the illustrated normal position, they are equally easily read. Near each station inscription or properly associated therewith is an aperture 28 in the face of the drum through which may be inspected and read the counter or meter indicating the 25 number of tickets sold, as will be more fully described.

30 35 Rather than continuing the description of the mechanism carried by the type drum, it will be convenient, first to describe the mechanism for feeding the tickets or blanks upon the periphery of the drum, and subsequently 40 describe the selective connections.

Above the top of the periphery of the printing drum is a hopper or magazine 30, consisting of a four-walled structure, in which are deposited face down a stack of 45 blank cards or tickets 31. These may be partially printed, for example, with the name of the railway or route, a series number, legal notices and reservations, and the like, with blank spaces for the name of the 50 destination or the names of the stations between which the passage is to be made.

The lowermost ticket rests upon a bottom plate 32, and is held there frictionally against displacement. A slot or space is left 55 at the right and left hand walls, so that a feeder plate 33 may enter at the right and force the bottom-most ticket out at the left. The bottom plate 32 is shown inclined so that its left extremity is in close proximity 60 or tangent to the periphery of the rotary drum.

When the ticket is thrust out by the feeder plate 33, it passes directly upon the periphery of the drum, and thence beneath a pressure roller 35, which bears against or toward

the periphery of the drum, and takes up and carries forward the feed of the ticket. During this action the ticket is sufficiently pressed against the inked type of the printing plate 16 to properly take the impression of the names of the station or stations which have been selected by means of the push button 25*. The pressure roller 35 is preferably driven by a gear 36, mounted on the axle 37 of the pressure roller, and meshing with the gear 17 at the rear side of the drum. By reason of this and by the fact that the periphery length of the pressure roller corresponds with one unit of advance of the drum, I am enabled to employ the roller as 70 a dating device, and date printing type 38 are indicated on the roller. This will impress on the rear or upper side of each ticket the date of sale. An inking device 39 may be employed to supply ink to the date 75 type 38.

The ejector or outfeeding slide 33 is shown as fitted to move into and from the hopper along an extension or guide 41, which is slotted underneath to permit a rack 42, formed at the lower side of the slide, to protrude downwardly where it may be engaged by an actuating gear 43. The shaft on which the gear 43 is mounted carries also a pinion 44, which is engaged by a toothed segment or rack 45, fitted to move up and down in engagement with the pinion by means of its carrying lever 46, which is normally pulled up by a spring 47, but adapted to be forced down through its bent extension or tail 48, which stands in the path of the finger 26*. This finger, as before stated, is one of the fingers 26, which has been thrust rearwardly to stand out in the path of the tail 48, as shown in Fig. 3.

By this mechanism the feed-operating finger, when set by the pressing of the corresponding selective button, cooperates with the tail 48 of the lever 46, so as to throw downwardly the rack 45 and rotate the pinion 44 and gear 43, which latter, acting on the rack 42, thrusts the ticket feed or ejecting slide 33 to the left in Fig. 1, thus outfeeding and thrusting the lowermost blank or ticket directly upon the top side or periphery of the rotary carrier or drum 15, at a point above the printing member or plate 16, corresponding to the selective button which has been pressed. The outfeeding ticket advancing substantially with the advance of the printing plate is smoothly and accurately laid in proper position, and during its movement out from the hopper it is engaged by the pressure roll 35 and forced intimately against the inked type of the printing member, so as to receive the name of the station and other printed matter below, while at its upper or rear side the ticket is printed with the date, as already explained. The ticket continuing its for- 105

ward movement from the printing point, passes directly into the channel or discharge chute 50, which carries it to the table or counter near to the ticket salesman or pur- 5 chaser.

We come now to the selective mechanism and details of the devices controlled by the selective buttons and carried by the rotary carrier or drum 15.

10 Each button 25 has direct or indirect mechanical connection to the feed operator or finger 26. The connection, as seen in Figs. 4 and 5, may consist in a pivoted lever 55, connected by a link 56 to a collar 57 on the finger 26. In some cases, as shown in Fig. 6, the button 25 may be directly on the finger 26. The finger or feed operator is shown in the form of a sliding rod extending from the front through to the rear of the rotary 15 carrier or drum. It slides in a sleeve 58 near its rear end, and is similarly guided by a shorter sleeve member 59 at the front. A plate spring 60 is shown, tending always to press the finger 26 forwardly to normal position. Fig. 4 shows the normal position, and Fig. 5 shows the shifted or set position after the button 25 has been pushed.

When the button is pushed and the feed operating finger is moved to operative position, it is desired to lock or latch it there until it has performed its functions. For 30 this purpose it is formed with a shoulder 62 near the front end, the same coöperating with a latch or lock piece 63, which is 35 pressed rigidly outward by plate spring 64. By this arrangement, when the finger is pressed to the Fig. 5 position, the latch or lock 63 springs from the Fig. 4 to the Fig. 5 position behind the shoulder 62, and the 40 parts are thus held until subsequently re- 45 sored, as will be explained.

This act of selectively setting the finger 26 places it in position to strike and thrust upwardly the bent lever near the top of the 45 machine through which a blank ticket is fed upon the periphery of the drum. At the same time I provide for starting into operation the driving motor 19. This being done automatically saves the attention of the operator. A contact 67 is mounted at the rear 50 of each finger 26. Extending behind each contact 67 is a strip contact 68. The various strip contacts are mounted radially, as seen in Fig. 2, each having an insulated connection 69 at the rear face of the drum. All of the contact strips 68 are in electrical connection with a simple contact ring 70, which turns with the drum and is in constant contact with a brush 71, which also is insulated. 55 The electrical circuit will pass through the described parts, and through the general or non-insulated parts of the machine, and thence through a battery and the motor. Thereby the motor will be started into operation whenever one or more of the fingers 60

26 are thrust rearwardly by the selective buttons.

As an automatic resetting or restoring means I show an extension 74 on the lock or latch piece 63, and a swinging resetting dog 75, which normally stands as in Fig. 4, but swings outwardly to the position 75* shown in Figs. 1 and 5. The entire series of dogs 75 is arranged to pass beneath a resetting cam or contact 76, located just beyond the ticket feeding hopper; thereby the drive continues until the printing member has passed the hopper, received a ticket and printed and discharged the same. The dog 75 is then restored, as stated. This forces back 80 the lock or latch 63 from the Fig. 5 to the Fig. 4 position against the resistance of the spring 64. When the latch reaches the normal position shown in Fig. 4, the spring 60 comes into play to thrust forwardly the 85 rod or finger 26, which thus takes its normal place, at which it holds the latch restrained, ready for a new operation.

It will be understood that the restoration of the feed operator or finger 26 simultaneously separates the contacts 67, 68, and discontinues the drive. The momentum of the parts may suffice to carry the drum around to normal position, at which it will be stopped by the device 20 before mentioned; 90 but momentum may be supplemented by turning the drum by hand, and the addition of a peripheral weight 78 will assist in restoring the parts to normal position in which the several inscriptions on the dial 100 of the drum will read correctly.

In order to give each ticket a serial or consecutive number, a numbering device 80 is employed, there being one for each of the selected mechanisms described. This numbering device may consist of shiftable type wheels in a usual manner, and may be operated by a pawl 81, shown as mounted on the resetting dog 75. The numbers which appear at the periphery of the drum project 110 through an aperture in the printing member or plate 16, and these impress the proper number on the ticket.

At the same time count may be kept of the numbers of tickets sold to each destination, thus enabling the total business to be reckoned up at will. For this purpose a counting device 83 of any usual type may be employed, preferably operated by a pawl 84, driven by a link 85, connected with the 115 latch or lock piece 63. The counting device numbers, which indicate the count of the tickets, appear through the apertures 28 at the face or dial of the drum, as already stated, each of these corresponding with one 120 of the push buttons 25 and inscriptions 27.

The various devices and operations described are controlled and operated selectively by the pressing of the desired button. The pressure of the button shifts the finger 130

26, and this closes and afterward opens the circuit of the driving motor. The lock 63 springs into position to hold the finger where it is set. This act determines the subsequent operation of the mechanism. The lock as well as the finger takes a set position upon the pressing of a button. The lock itself is available as a mechanical part able to effect other operations. It is more available than the finger, and therefore I preferably operate from the lock or latch 63, as described, the resetting dog 75, the numbering mechanism 80, and the counting mechanism 83.

15 The operator is not limited to the issuing of a single ticket at a time, that is, one ticket for each rotation. Obviously if he simultaneously presses two buttons, or even more, the corresponding feed operating fingers, 20 two or more in number, will be set, and each in its turn will cause the ejection and depositing of a ticket upon the drum, to be printed and delivered down the chute. The current will not be cut off until the last of 25 the fingers has been restored through the described resetting devices.

It will thus be seen that I have described a ticket printing machine embodying the principles and attaining the advantages of 30 the present improvement. Since, however, many matters of combination, arrangement, mechanism and detail may be variously modified without departing from the underlying principles, no limitation is intended 35 except as set forth in the appended claims.

What is claimed is:

1. A ticket printing machine, comprising a rotary carrier with printing members thereon, selecting members or buttons carried by the carrier, a feed-operator or finger set by each selective member, and a ticket feed mechanism actuated or timed by said feed-operator, whereby a ticket is fed selectively to the desired printing member on the carrier.
2. Machine as in claim 1 and wherein a means or device is employed to restore the feed-operator to original position after the same causes the feed of a ticket.
3. Machine as in claim 1 and wherein a presser is arranged to press each ticket to the printing member as they advance in unison beyond the feed position.
4. Machine as in claim 1 and wherein a date printing roller is arranged to print at the reverse side and press each ticket to the printing member as they advance in unison beyond the feed position.
5. Machine as in claim 1 and wherein the

fed and printed ticket is discharged to a 60 delivery chute.

6. A ticket printing machine having a rotary carrier with printing members around the same, ticket feeding means comprising a magazine above the rotary carrier and a 65 device for outfeeding a ticket therefrom and depositing it on a selected printing member on the carrier, and selective devices on the carrier for actuating or timing said outfeeding device.

7. Machine as in claim 1 and wherein the ticket feed mechanism comprises a magazine, a device for outfeeding a ticket therefrom, and connections engaged or actuated by the finger carried by the rotary carrier 75 for operating the outfeeding device at the proper time.

8. Machine as in claim 1 and wherein the carrier carries a ticket numberer for each printing member, and connections actuated 80 at each printing for advancing the numberer.

9. A ticket printing machine comprising a rotary drum, a series of printing members around the same, a series of corresponding 85 selective buttons on the drum, a feed-operator or finger for each button carried by the drum and set by its button, and ticket feeding mechanism actuated or timed by said feed-operator to feed a ticket to the corresponding printing member.

10. Machine as in claim 9 and wherein a drive motor rotates the drum, and connections operated in setting the feed-operator for starting the motor.

11. Machine as in claim 9 and wherein a drive motor rotates the drum, and connections operated in setting the feed-operator for starting the motor, and in restoring it for cutting off power.

12. Machine as in claim 9 and wherein a lock or latch retains the feed-operator finger when set.

13. Machine as in claim 9 and wherein a lock shifts to retain the finger when set and 105 to advance a ticket numberer.

14. Machine as in claim 9 and wherein a lock shifts to retain the finger when set and to advance a ticket counter.

15. Machine as in claim 9 and wherein 110 each feed-operating finger is provided with a lock, holding it when set, a resetter shifted by said lock, and means exterior to the drum for shifting the resetter to restore the parts after each feeding-operation.

In testimony whereof, I have affixed my signature hereto.

MAURICE RALPH HOWARD.
